UNITED STATES PATENT OFFICE.

GEORGE R. LOCKWOOD, OF ST. LOUIS, MISSOURI.

ENVELOP.

No. 900,751.

Specification of Letters Patent. Patented Oct. 13, 1908.

Application filed September 30, 1907. Serial No. 395,070.

To all whom it may concern:

Be it known that I, GEORGE R. LOCKWOOD, a citizen of the United States, residing at St. Louis, in the State of Missouri, have invented 5 a certain new and useful Envelop, of which the following is such a full, clear, and exact description as will enable any one skilled in the art to which it appertains to make and use the same, reference being had to the accompanying drawings, forming part of this specification.

My invention relates to envelops, and more particularly to envelops suitable for mailing small articles of merchandise.

My envelop is especially adapted for mailing thin, flat articles such as photographic prints, film negatives and the like. It may, however, be used for various kinds of small articles of merchandise.

20 In the accompanying drawings, which illustrate one form of envelop made in accordance with my invention, together with a slight modification thereof, Figure 1 is an inside view of the envelop, the two parts thereof being unfolded. Fig. 2 is a view similar to Fig. 1 but showing a slight modification. Fig. 3 is an outside view of the envelop shown in Fig. 2, the parts being folded together. Fig. 4 is a cross-sectional view.

30 Like marks of reference refer to similar parts in the several views of the drawings.

10 are the two main parts of the envelop which are preferably rectangular or substantially rectangular in form. These parts 35 are integrally connected and are adapted to be folded together along the line 11, which may be creased to facilitate the operation of folding.

40 12 are the side flaps which are formed integral with the main parts 10 so that when folded along the lines 13 integral closures will be formed for the outer sides of the pockets. The side flaps 12 are of slightly less width than the main parts 10 so that the inner edges 45 14 of said flaps lie at some distance from the fold 11, the object of this being to facilitate the insertion and withdrawal of the articles in the pockets. The inner edges 14 are also preferably each provided with a recessed portion 15 to further facilitate the insertion and withdrawal of the articles.

50 16 are end flaps which are formed integral with the main parts 10 and which are folded

along the lines 17 so as to overlap the ends of the side flaps 12. The end flaps 16 are 55 gummed, or otherwise permanently secured to the side flaps 12, thus completing the formation of the pockets for holding the articles of merchandise. The end flaps 16 are preferably provided with bevels 18 at their outer 60 ends and bevels 19 at their inner ends.

In order to secure the two parts of the envelop in their folded position, I provide the pockets with eyelets 20 adapted to register with each other. In the form shown in Fig. 65 1, two of these eyelets are provided, one in each pocket arranged centrally and adjacent to the outer side, while in Figs. 2, 3 and 4 I have shown the envelop provided with four of these eyelets arranged at the ends of the 70 pockets. In order to secure the parts together paper fasteners 21 may be passed through the eyelets 20, or the parts may be secured together by means of a cord or other flexible fastening means passing through the 75 eyelets.

It will be evident that, while my envelop is made with the smallest possible amount of material, it is neat in appearance and durable and can be readily inspected by reason of the 80 simplicity of the fastening means for securing the two parts of the envelop in folded position.

Having fully described my invention, what I claim as new and desire to secure by Letters Patent of the United States is:

1. An envelop having two integrally connected main parts, side flaps opposite the connecting portion of said main parts and folded on said main parts to form the bodies of pockets with integrally closed sides, said flaps being of less width than said main parts, end flaps overlapping and permanently secured to said side flaps to close the ends of the pockets, said pockets being adapted to 95 be folded together and provided with fastening means for securing them in folded position.

2. An envelop having two integrally connected main parts, side flaps opposite the 100 connecting portion of said main parts and folded on said main parts to form the bodies of pockets with integrally closed sides, said side flaps being of less width than said main parts, end flaps overlapping and permanently secured to said side flaps to close the ends of 105

the pockets, said end flaps being beveled at their inner ends and extending to the connecting portion of said main parts, said pockets being adapted to be folded together 5 and provided with fastening means for securing them in folded position.

In testimony whereof, I have hereunto set

my hand and affixed my seal in the presence of the two subscribing witnesses.

GEORGE R. LOCKWOOD. [L. S.]
